(57) **CLAIM**

The ornamental design for a combined USB memory device and watch, as shown and described.

DESCRIPTION

The claimed combined USB memory device and watch is a small, portable timepiece with data-storage function.

FIG. 1 is a front elevational view of a combined USB memory device and watch showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is an exploded perspective view showing the combined USB memory device and watch separated from the watch. The watchband in FIG. 7 is shown in a fastened position.
